United States Patent Office

Des. 229,944
Patented Jan. 15, 1974

229,944

TELEPHONE RECEIVER HOLDER

Dorothy I. Eddy, 7141 Country Club Lane,
Kansas City, Mo. 64114

Filed Dec. 13, 1971, Ser. No. 207,713

Term of patent 3½ years

Int. Cl. D14—03

U.S. Cl. D26—14 A

Fig. 1.

Fig. 2.

Fig. 3.

Fig. 4.

Fig. 5.

FIG. 1 is a front elevational view illustrating a telephone receiver holder;

FIG. 2 is a top plan view of the telephone receiver holder;

FIG. 3 is a bottom plan view of the telephone receiver holder;

FIG. 4 is a rear elevational view of the telephone receiver holder; and

FIG. 5 is a side elevational view of the telephone receiver holder, the opposite side being identical to the side shown.

I claim:

The ornamental design for a telephone receiver holder, as shown.
